UNITED STATES PATENT OFFICE.

JAMES D. WILLMOTT, OF PHILADELPHIA, PENNSYLVANIA, ASSIGNOR TO WILLIAM H. HORN & BROTHER, INCORPORATED, OF PHILADELPHIA, PENNSYLVANIA, A CORPORATION OF PENNSYLVANIA.

KNEECAP OR ELBOW BANDAGE.

Application filed February 4, 1919. Serial No. 274,862.

To all whom it may concern:

Be it known that I, JAMES D. WILLMOTT, a subject of the King of Great Britain and Ireland and the Isle of Man (having declared my intention of becoming a citizen of the United States), residing in Philadelphia, Pennsylvania, have invented Kneecap or Elbow Bandages, of which the following is a specification.

10 In order to support and protect an injured or unhealthy knee or elbow joint it is customary to apply thereto a bandage in the form of a tubular fabric sleeve which includes circular courses of rubber or other 15 elastic threads or strips. This sleeve or bandage has a diameter less than that of the limb for which it is designed so that when in use its elastic elements are maintained in a stretched condition in order to cause it as 20 a whole to exert a compressive action on the affected parts.

It has been found however, than an elastic bandage of this type causes discomfort and annoyance by reason of the fact that at the 25 rear of the knee or other joint, it will form in relatively thick folds or wrinkles by reason of the overlapping of its parts when the said joint is flexed, and one object of the present invention is to provide a bandage of the above type in which the formation of these folds shall be reduced to a minimum and the nature of that part of the bandage where some slight wrinkling will unavoidably occur, shall be such as to prevent such 35 overlapping as will pinch the skin of the wearer or cause discomfort under the conditions noted. At the same time it is desired that the construction, while being soft and flexible over a definite area at the rear of 40 the joint, shall be such as not to interfere with the required functions of the bandage nor to cause it to have other than a smooth appearance.

I further desire to provide a surgical 45 bandage of the type above noted which shall include a part of relatively non-elastic material, preferably of a thickness less than the remainder, having such a construction as to prevent distortion of the bandage as a whole 50 and cause it to perform its desired functions while avoiding the formation of thick and uncomfortable folds or overlapping portions when the knee or other joint to which the bandage is applied, is flexed.

These objects and other advantageous ends 55 I attain as hereinafter set forth, reference being had to the accompanying drawings, in which,

Fig. 1 is a rear elevation of a knee joint showing my improved bandage as applied 60 thereto;

Fig. 2 is a side elevation of the joint and bandage shown in Fig. 1, illustrating the parts in the positions occupied when said 65 joint is flexed;

Fig. 3 is an enlarged diagrammatic elevation, showing the detail construction of that 70 part of the bandage whose construction has been modified according to my invention; and

Fig. 4 is an enlarged fragmentary elevation also diagrammatic, further illustrating 75 the construction of the bandage.

In carrying out my invention I preferably utilize a circular or other knitting machine 75 to form a more or less elongated tube 1 of knitted ribbed fabric having in its successive courses relatively thick encircling threads, strips or bands 2 of soft rubber, preferably provided with a cotton or other 80 covering so that said tube as a whole is capable of such expansion as will permit of a material increase of its diameter at any point, although it is relatively inflexible longitudinally.

If this bandage be applied to a knee joint for example, it will, when said joint is flexed, form in relatively heavy folds or wrinkles at the back thereof, and these, by reason of their size and position, will be 90 uncomfortable and in many instances will so overlap as to pinch the skin at the rear of the joint.

According to my invention I omit the rubber threads or bands from a definite area for 95 which purpose I cut them in a line $x-x$ parallel with the longitudinal center line of the bandage, at that part thereof which is to be at the center of the rear of the joint, i. e., in that part of the bandage which is folded 100 or wrinkled to a maximum extent when the joint is bent.

In a typical case, the successive courses of the rubber strips are cut for a length of from one and one-half inches to two inches, 105 and the two uppermost pairs of adjacent ends on the opposite sides of the line of the cut are stripped back from the cotton or

silk ribbed fabric 3 for a suitable distance, —for example, one-half inch on each side, and are then knotted or tied together as indicated at 4. The two next lower pairs of 5 rubber ends are then similarly stripped back, but for a distance of two ribs further, in a typical case, after which they likewise are respectively tied or knotted together as indicated at 4^a. The stripping back and tying 10 together of the successive pairs of the rubber thread ends is thus continued until half of those which have been cut have been so treated, after which the remaining pairs of ends are similarly stripped back and tied 15 but for decreasing, instead of increasing lengths, until the two last and lowest of the cut strips have been united in pairs on opposite sides of the line x—x along which they were originally cut. There is thus defined 20 a substantially diamond shaped area y, elongated circumferentially of the bandage and of a thickness less than the remainder or body thereof, in which area there is a total absence of the relatively thick rubber 25 threads or strips, and it is noted that the knots in which the cut strips terminate are preferably formed under tension so that when finished they are drawn into and practically concealed in the body of the ribbed 30 fabric at the margins of the above noted area.

I then insert in this relatively thin area y, preferably by means of a darning or similar needle, a thin non-elastic thread 5, carrying it from a knot 4 at the one side of the top of said area, across the same parallel with the uncut rubber threads and through or around the opposite knot 4 and the ribbed part 3 of the fabric associated therewith. It 10 is then carried down and similarly threaded back through the unaltered ribbed fabric 3 in the opposite direction, parallel with and below the first length so inserted, to and through or around the knot 4^a at the opposite side of the area y, immediately below and to one side of the knot 4. It is then passed down and again carried across through the ribbed fabric 3 to the next lower knot on the opposite side of the area y, — 15 being so carried alternately back and forth and attached, until the bottom of said area is reached, when its free end is knotted or non-removably fixed in the fabric of the bandage.

55 The relatively thin, non-elastic thread thus practically replaces the thicker elastic threads which have been removed from the area y and connects together the opposite pairs of knotted or tied ends so that said 60 area is substantially inflexible circumferentially as well as longitudinally of the bandage, while being soft and flexible. Said bandage is thus maintained in shape and at the same time that portion thereof lying at

the back of a knee joint for example, and 65 which would form in wrinkles or folds when said joint was bent, is so reduced in thickness that what small folds or wrinkles may be actually formed are not annoying nor are they liable to pinch the skin. As a result of 70 this construction, the bandage while performing all of the functions required of it, is comfortable to wear and causes no annoyance even though the joint to which it is applied be bent to its fullest extent. 75

While for most purposes I preferably give a diamond or other elongated form to the area from which the thick elastic threads have been omitted, it is to be understood that such form may be widely varied without departing from my invention, since its shape would obviously be such as to best suit the bandage for application to the joint on which it is to be used.

I claim:

1. A tubular fabric bandage having courses including encircling elastic elements and having an area from which said elements are omitted; with relatively non-elastic elements extending circumferentially of 90 the bandage across said area and tying together the substantially opposite portions of the elastic elements.

2. A tubular bandage having courses including encircling elastic elements of 95 which certain are cut away to define an area from which said elements are absent; with relatively non-elastic elements connecting the substantially opposite ends of the elastic elements.

3. A tubular knitted bandage having courses including encircling elastic elements of which certain are cut away to define an area from which said elements are absent; with relatively non-elastic elements connecting the substantially opposite ends of the elastic elements, the two pairs of free ends of each pair of adjacent elastic elements being respectively united. 100

4. A tubular knitted bandage of ribbed 110 fabric including circumferentially extending elastic elements, certain of which are omitted from a predetermined area of the fabric, the two pairs of free ends of each pair of adjacent courses being united along 115 the margins of said area.

5. A tubular knitted bandage of ribbed fabric including circumferentially extending elastic elements, certain of which are omitted from a predetermined area of the 120 fabric, the two pairs of free ends of each pair of adjacent courses being united along the margins of said area; with non-elastic means for preventing substantial circumferential separation of the opposite united 125 pairs of ends.

In witness whereof I affix my signature.
JAMES D. WILLMOTT.
